UNITED STATES PATENT OFFICE.

JOHN F. HINES, OF PITTSBURG, PENNSYLVANIA.

TELEPHONE-RECEIVER HOLDER.

973,198.

Specification of Letters Patent. Patented Oct. 18, 1910.

Application filed November 18, 1909. Serial No. 528,792.

To all whom it may concern:

Be it known that I, JOHN F. HINES, a citizen of the United States of America, residing at Pittsburgh, in the county of Allegheny and State of Pennsylvania, have invented certain new and useful Improvements in Telephone-Receiver Holders, of which the following is a specification, reference being had therein to the accompanying drawing.

This invention relates to a telephone receiver holder, particularly designed for desk telephones or that type of telephones having a pedestal adapted to support the transmitter and receiver.

The primary object of my invention is to provide a telephone with a holder adapted to normally support the receiver in proximity to the transmitter whereby it will not be necessary for a person to manually hold the receiver when transmitting a message.

Another object of the invention is to provide a telephone receiver holder with simple and effective means for maintaining the telephonic circuit closed, when the receiver is removed from the receiver switch-arm.

A further object of this invention is to provide an adjustable receiver holder for telephones that can be easily adjusted to correctly position a receiver relative to a person's head, whereby a message can be received and conveniently acknowledged without using the hands to hold the receiver to the ear.

A still further object of the invention is to accomplish the above results by a receiver holder that is simple in construction, durable, easily applied to a telephone, and highly efficient for the purposes for which it is intended.

With these and such other objects in view as may hereinafter appear the invention consists of the novel construction, combination and arrangement of parts to be herein-after specifically described and then claimed.

Reference will now be had to the drawing forming a part of this specification, wherein there is illustrated a preferred embodiment of the invention, but it is to be understood that the structural elements thereof can be varied or changed, as to the size, shape and manner of assemblage without departing from the spirit and scope of the invention.

In the drawings:—Figure 1 is a horizontal sectional view of the telephone, showing my receiver holder in plan as attached

thereto. Fig. 2 is a front elevation of the same. Fig. 3 is a horizontal sectional view of a pedestal clamp adapted to form part of the holder, and Fig. 4 is a side elevation of a detached receiver-support.

The telephone receiver holder consists of a bracket adapted to be suitably clamped to the pedestal of a desk telephone, one end of the bracket being secured to the telephone pedestal, while the opposite end is provided with a receiver-support. The bracket comprises a vertical metallic strap 1 having a right angular extension 2 at the upper end thereof. The strap 1 adjacent to its lower end is provided with an opening 3 for a bolt 4. Upon the bolt at each side of the strap 1 are arranged washers 5 and 6 and against the washer 5 is arranged a resilient clamp 7 having an offset portion which is held against the washer 5 by a nut 8 screwed upon the bolt 4, although the bolt 4 can be provided with a fixed head that will serve the same purpose. The bolt extends through the offset portion and the nut 8 is positioned within the offset portion of the clamp. The resilient clamp 7 is adapted to embrace the pedestal 9 of a desk telephone, and the free ends of said clamp are held by a screw bolt 10 and a nut 11, said bolt and nut frictionally securing the clamp 7 upon the pedestal. The bolt 4 is provided with a nut 12 and upon the bolt is mounted the end link 13 of a chain 14, said link being bound against the washer 6 by the nut 12, which also serves to hold the clamp 7 in engagement with the strap 1. The other end link of the chain 14 is attached to a hook 15, which is employed for holding the receiver switch-arm 16 of the pedestal 9 in a lowered position, with the telephonic circuit closed when the receiver is removed from the switch-arm. The upper end of the strap 1 adjacent to the extension 2 supports another resilient clamp 17 having an offset portion which is held in engagement with the strap 1 by a bolt 18, washers 19 and a nut 20. The bolt extends through the offset portion of the clamp 17. The clamp 17 is adapted to embrace the neck 21 of the pedestal 9 which supports the transmitter 22, the free ends of the clamp 17 being secured together by a bolt 22 and a nut 23. The clamps 17 and 7 constitute means for retaining the receiver holder in engagement with the telephone.

The outer end of the extension 2 is provided with a vertical screw bolt 24 and a

nut 25, said bolt and nut retaining a receiver-support 26 upon the outer end of the extension 2. The receiver-support 26 is provided with a longitudinal slot 27, whereby the support can be adjusted relative to the extension. One end of the support 26 is bent upwardly, as at 28, and riveted or otherwise secured to the upwardly bent end of the support 26, as at 29, is a bifurcated rest-piece 30 adapted to support the small end of a receiver 31, while the opposite end of the support is provided with a rest-piece 32 adapted to support the large end of the receiver 31. These two rest-pieces co-operating in supporting the receiver 31 in a horizontal position. The rest-pieces, as well as the remainder of the holder, are constructed of light and durable metal, and it is through the medium of the slotted support 26, bolt 24 and nut 25 that I am enabled to place the large end of the receiver 31 in proximity to a person's ear transmitting or receiving a message over the telephone.

25 The receiver is adapted to be normally positioned in the support 26, with the hook 15 in engagement with the switch-arm 16. When it is desired to receive or transmit a message, it is only necessary to remove the hook 15 from the arm 16 and open the telephonic circuit. However, it is optional with the user of the telephone whether the re-

ceiver remains in the holder 26 or whether it is positioned upon the arm 16, as shown in Fig. 1 of the drawings.

Having now described my invention what I claim as new, is:—

A telephone receiver holder comprising the combination with a pair of clamps adapted to be connected to a telephone pedestal each having an offset portion, of a one piece bracket having a vertically-disposed portion arranged in parallelism with respect to the pedestal and further embodying a right-angularly disposed portion, bolts extending through the vertical portion of the bracket and the offset portions of the clamps, for supporting the bracket from the clamps, means carried upon the inner end of the bolt within the offset portions and upon the outer end exteriorly of the offset portions for connecting the bracket to the clamps, a horizontally-disposed support adjustably-mounted upon the free end of said right-angularly disposed portion of the bracket, and rest-pieces secured to the ends of said horizontally-disposed support.

In testimony whereof I affix my signature in the presence of two witnesses.

JOHN F. HINES.
